FLOW RESTRICTOR FOR HEATING SYSTEMS

William K. Simpson, Waterbury, Conn., assignor to Hoffman Specialty Company, Waterbury, Conn., a corporation of Illinois

Original application July 22, 1932, Serial No. 623,955. Divided and this application December 17, 1934, Serial No. 757,887

1 Claim. (Cl. 138—45)

This application is a division of my pending application for Letters Patent for improvement in Heating systems filed July 22nd, 1932, Serial No. 623,955.

This invention relates to a heating system which includes a plurality of radiators and a pipe line or conduit system connecting the radiators with a boiler.

In one-pipe steam heating systems, especially those in which steam is supplied at timed intervals, there is often trouble in obtaining even distribution of the heating medium.

Under certain conditions the boiler is not running at its full capacity, consequently the quantity of heating medium supplied is insufficient to fill all of the radiators. As a result radiators near the boiler are often filled entirely, while those at the end of the system contain little or no heating medium.

A further trouble is due to uneven distribution of heating medium when oil burners are used. The heat of the oil burner is so intense that the heating medium is generated very rapidly, so that radiators close to the boiler fill very quickly. If the thermostatic regulator which controls the oil burner happens to be in a room which heats quickly, the burner is closed off prematurely, and the radiators at the far end of the system will not receive their full amount of heating medium.

The object of my invention is to prevent the above mentioned objections. I accomplish this by inserting in suitable sections of the conduit system, port-forming partitions characterized as hereinafter stated, including ports of variable area, adapted to reduce to any desired extent the effective area of said conduit portions, and thereby independently regulate the supply of heating medium to each radiator, so that, for example, if three radiators close to the boiler are completely filled with heating medium, a proper adjustment of the ports in said partitions will cause these radiators to be only partially heated, a sufficient quantity of the heating medium being caused to pass on to other radiators.

Of the accompanying drawing forming a part of this specification,—

Figure 1 is a sectional view showing one of my improved flow restrictors associated with a radiator-supplying conduit section.

Figure 2 is a side view of the lead screw shown by Figure 1, somewhat enlarged.

Figure 3 shows in perspective two parts of the adjustable port-forming partition shown by Figure 1.

Figure 4 is a section view showing the partition

shown by Figure 1, associated with a union elbow.

Figure 5 is a side view on a reduced scale of a concealed radiator, and the conduit portion supplying the latter, said conduit portion including the union elbow and partition shown by Figure 4. 5

The same reference characters indicate the same parts in all of the figures.

A heating system to which my invention relates comprises a plurality of radiators and a conduit system connecting the radiators with a boiler. 10

Included in the conduit system are variable port-forming partitions characterizing the invention. Each partition includes a fixed or non-adjustable member, and adjustable members movably connected with the fixed member, said members being formed to provide a port which is variable in area by movement of the adjustable members relative to the fixed member.

The partition shown by the drawing includes a fixed septum 60 which is formed in and integral with a section of the conduit system. Said section, as shown by Figure 1, includes a portion 45 containing a valve disk 47, and a fixed septum or partition member 60 having an orifice 61 constituting the inlet controlled by the valve body 47. The adjustable member is composed of two parts or shutters 62 (Figure 3), slideable in opposite directions on the fixed member 60 to cooperate with the orifice 61 in forming a variable orifice 63. The shutters 62 are provided with ears 64, one having a tapped orifice 65, and the other a tapped orifice 66, one orifice having a right hand, and the other a left hand thread. The diameter of the orifice 65 is greater than that of the orifice 66. A lead screw 67 having right and left hand threaded portions 68 and 69 corresponding with the threads of said orifices, is engaged with the ears 64 so that rotation of the screw moves the shutters simultaneously toward or away from each other. One end portion 40 of the screw is journaled in an internal bearing 70. The opposite end portion is journaled in a bearing 71, and projects through the wall of the conduit section. A knob 72 secured to the projecting end of the lead screw has an inner end 45 constituting a valve fitting a recess or seat surrounding the bearing 71, and preventing escape of fluid. The knob has a detachable screw thread connection with the projecting end of the lead screw. A washer or collar 73 fixed to the lead screw and bearing on the internal surface of the conduit section, cooperates with the knob 72 in preventing endwise movement of the lead screw. Said collar also frictionally opposes rotation of the lead screw.

5 The diameter of the threaded portion 69 of the lead screw is less than that of the portion 68, so that the portion 69 may be passed loosely through the larger tapped orifice 65 without engaging and being obstructed by the internal thread of said orifice.

10 The knob 72 seals the joint at the bearing 71 and acts as a lock nut preventing rotation of the lead screw 67. Adjustment is made by first 15 removing the knob 72, then applying a tool to the projecting end of the lead screw and rotating the latter thereby, and then replacing the knob. The internal thread of the knob may be so formed that there will be little, or no frictional resistance to the rotation of the knob until its inner 20 end contacts with the bearing 71.

In practice, the shutters 62 are located below 25 the port opening 61 and the valve disc 41 is above said opening, so that the shutters are held closely against the partition 60 partly by pressure of the heating medium, this pressure taking up any play of the shutters due to any inaccuracies of the screw and the orifices 64 and 65, the direction of flow being against the exposed 30 surface of the shutters.

It will be seen that the port formed by the described partition may be varied wholly by rotating the lead screw, no separation of conduit parts being required.

35 To adjust the shutters 62, the lead screw may first be turned to cause the shutters to meet and close the orifice 61. Then with a known pitch to the threads 68 and 69, it will be possible to provide an orifice 63 of a given area by giving 40 the lead screw a given number of turns. For example, to set the orifice for a radiator containing forty square feet of radiation, the lead screw may be given four turns.

In Figure 4, the conduit part or section is a 45 union elbow 15, the fixed member 60 of the port-forming partition being between the ends of the elbow. The adjustable member of the partition and the means for varying the area of the port are as described with reference to Figure 1.

The elbow 15 may supply steam to a radiator 50 16, (Figure 5), concealed by a casing 71 having upper and lower grilles 18 and 19. The heat output of the radiator is usually controlled by 55 a damper adapted to close and open the upper grille. When this damper is opened there is a "stack" effect which causes rapid condensation in the radiator and a high heat output. When the damper is closed, partly or completely, the circulation of air is throttled down and the heat output reduced.

Union elbows with ports, as shown in Figure 4, are preferred in radiators of the type shown by Figure 5, where there are no inlet valves for shutting off the heating medium. The radiator is always filled with heating medium and its heat 5 output is controlled by a shutter in the back of the grille 19. When no heat is required the grille is closed, and with no appreciable circulation of air past the radiator, only a small portion of heat will be given off. With the shutter 10 open and air circulating through the radiator, the heat output of the radiator likewise increases.

In concealed radiator systems there is difficulty in balancing up the flow of heating medium, which difficulty is overcome by inserting 15 the adjustable port-forming partition in the union elbow 15.

It will now be seen that the above described flow restrictor includes means for preventing displacement of the adjustable members 62 from 20 port-varying positions, said members being movable only by rotation of the lead screw 67 which cannot move endwise, so that the members 62 are always maintained in port-varying positions.

25 I claim:

In a heating plant conduit system, a flow restrictor including a conduit section provided with an internal partition having an orifice, two adjustable partition members or shutters movable only simultaneously in opposite directions on the 30 internal partition to cooperate with said orifice in forming a variable port, said members having ears provided with right and left tapped orifices, a lead screw having right and left internal screw threads engaged with said ears, a washer fixed to the screw and bearing on the internal surface of the conduit section, said screw having an outer end projecting outwardly from said section, and an internally threaded knob engaging 35 an external thread on the projecting outer end of the screw, the inner end of the screw being journaled to rotate without endwise movement in a bearing in the conduit section, said knob constituting a valve preventing the escape of 40 fluid from the conduit section, and constituting also a lock nut preventing accidental rotation of the lead screw, said washer cooperating with the knob and with said bearing in preventing end- 45 wise movement of the lead screw so that said shutters are movable only by rotary movement of the lead screw, and simultaneously in opposite directions.

55 WILLIAM K. SIMPSON.
